UNITED STATES PATENT OFFICE.

JOHN H. MANNING, OF HARTWELL, OHIO.

SAFETY DEVICE FOR ELEVATORS.

SPECIFICATION forming part of Letters Patent No. 320,374, dated June 16, 1885.

Application filed December 29, 1884. (No model.)

To all whom it may concern:

Be it known that I, JOHN H. MANNING, of Hartwell, in the county of Hamilton and State of Ohio, have invented certain new and useful 5 Improvements in Safety Devices for Elevators, of which the following is a specification.

My invention relates to safety devices for preventing accidents with hatchway-elevators operated by power, and has for its object 10 the prevention of that class of accidents which are caused by persons upon one floor reaching into the hatchway and raising or lowering the elevator to the floor they are on by manipulating the tiller-rope; and it consists in a novel 15 combination of elements whereby a person, in order to move the tiller-rope, must be in the cab, all of which will be fully explained hereinafter.

In the accompanying drawings, Figure 1 is 20 a section of the floor of an elevator-cab, showing my improved safety device; Fig. 2, an enlarged elevation of the device, and Fig. 3 a plan thereof.

Similar letters of reference indicate similar 25 parts.

A is the floor of an elevator-cab of any desired form or construction.

B is the customary tiller rope or bar, as the 30 case may be, which, when pulled upward, (as is the custom,) causes the elevator to descend, and when pulled downward causes the elevator to ascend, in the hatchway through which the cab travels. The tiller or bar B passes through the floor A of the cab, and from bottom to top of the hatchway.

C is an inverted standard or housing secured to the under side of floor A, having lugs C' at one end and lugs C² at the other end thereof. Between the lugs C' is pivoted 40 the lever D, one end of which carries the sliding or adjustable weight d and the other end the arm or pintle d'. Between the lugs C² is pivoted the lever E, upon the outer extremity of the long arm e' of which is mounted the 45 pedal or foot-piece F. The arm d' of the lever D engages with the lever E at e, either by entering a hole formed to receive it in said lever or by any suitable connection, in such a manner, however, that motion of the lever 50 E produces a motion of the lever D through the arm d', and, conversely, motion of the lever D produces motion of the lever E through

the same arm d'. The short arm e² of the lever E is bent downward, or at right angles to the long arm e', and is pivoted to the parallel arms g g of the binder G, Fig. 3. The binder G, when drawn toward the immovable abutment C³ of the housing C, presses the rope or bar B against said housing and prevents the independent movement of the rope 60 until the binder is forced away from it, as shown by the dotted lines of Fig. 2. The normal position of the levers D and E, pedal F, and binder G is shown by full lines of Fig. 2, and in this position the tiller-rope B is 65 firmly gripped between the immovable abutment C³ and binder G, and prevented from moving up or down until the operator presses his foot on the pedal F, when the pedal and other moving parts assume the positions 70 shown by dotted lines of Fig. 2, and the grip upon the tiller-rope B is released. The force with which the tiller-rope is gripped between the binder G and immovable abutment C³ of the housing C is regulated by the weight d 75 and by the compound levers D and E, the weight d being secured to the long end of lever D, and acting through the short end of said lever and arm d' upon the long arm of lever E, which latter lever in turn actuates 80 the binder or gripping piece G, through its short arm e², whereby the effect of said weight is multiplied several times in the pressure of the binder G against the tiller-rope B.

The utility of the device is obvious. Directly the pressure of the operator's foot is removed from the pedal F, the weight d, and levers D and E, and binder G take the positions shown by full lines of Fig. 2, and the tiller rope B is gripped tightly between the 90 binder G and face C² of the housing C, in which position no motion of the rope is possible, and consequently no person can move the cab of the elevator, excepting he first enters the cab and presses his foot upon the 95 pedal F and releases the grip of binder G on the rope or bar B.

I have shown my device as containing a compound lever and weight, and as operated by the foot of the person working the elevator-cab; but I do not wish to confine myself to the arrangement of parts shown, or the described method of operation, because the same effect can be had by varying the form and po-

sition of the device—as, for instance, it may be placed upon the roof of the cab and be worked by a hand-rod, or it may be finished and placed within the cab and be operated by a hand-lever; again, the lever D and lugs C' of housing C may be omitted entirely, and an arm provided at the short end of lever E, to which the weight is applied direct, and the weight may be displaced by a spring, the essential requisite of my improvement being a device which automatically grips the tiller-rope or bar when the attendant leaves the cab, and which can be operated to release the rope only by the return to the cab and by the pressure of the foot or hand of the person working the elevator.

A large number of accidents with passenger elevators grow out of strangers attempting to operate the cab and leave it while it is in motion. With my improved safety device the tiller-rope cannot be moved up or down, excepting the operator first presses down the pedal F, and when he leaves the cab the pedal rises and the binder G automatically grips the tiller-rope and stops the cab.

Having described my invention, what I claim is—

1. A safety device to prevent manipulation of the tiller-rope of an elevator by other than the person in the cab, consisting, essentially, of mechanism, substantially such as described, which, by the force of a weight or spring, automatically grips the tiller-rope upon the removal of the pressure of the hand or foot of the operator, and, conversely, releases the grip

upon the tiller-rope when such hand or foot pressure is reapplied, substantially as described.

2. A safety device to prevent manipulation of the tiller-rope of an elevator by other than the person in the cab, consisting of a movable gripping piece or binder operated by the force of a weight or spring acting through a lever which automatically presses the tiller-rope against an immovable abutment upon the exit of the operator from the cab, substantially as described.

3. In a safety device to prevent manipulation of the tiller-rope of an elevator by other than the person in the cab, the combination, with the housing C and binder G, of the levers E and D, and the weight d, whereby said binder is caused to grip the tiller-rope B by the force of said weight, substantially as described.

4. In a safety device to prevent manipulation of the tiller-rope of an elevator by other than the person in the cab, the combination, with the housing C and binder G, of the lever E and pedal F, whereby said binder is caused to release its grip upon the tiller-rope B by the pressure of the operator's foot upon said pedal, substantially as described.

In testimony whereof I have signed my name to the foregoing specification in the presence of two subscribing witnesses.

JOHN H. MANNING.
